UNITED STATES PATENT OFFICE.

HENRY W. SCHLUETER, OF OCEANPARK, CALIFORNIA.

FLOOR CONSTRUCTION.

1,177,278.

Specification of Letters Patent. Patented Mar. 28, 1916.

Application filed August 3, 1914. Serial No. 854,873.

To all whom it may concern:

Be it known that I, HENRY W. SCHLUETER, a citizen of the United States, residing at Oceanpark, in the county of Los Angeles, 5 State of California, have invented a new and useful Improvement in Floor Construction, of which the following is a specification.

The invention relates to building construction and more particularly to the construction of concrete buildings, piers, and the like.

The principal object of the invention is to provide a floor construction in which a series of primary concrete members may be cast and seasoned at any convenient point at any convenient time, and in which, after the primary members have been placed in their final position in the building, secondary locking members may be cast therearound forming a rigid unitary floor.

It is at the present time common practice to build large structures of concrete by employing expensive false work, but my invention has a peculiar utility and novelty over all such systems in that the primary members are cast before the erection of the building is started or during the erection at some other point, and these primary members are the forms for secondary locking members which are cast after the primary members are set in place. As it is necessary for the economical production of any type of building to provide large floor spans between the supporting beams, floor members if cast so as to be self-supporting and fill this large area would be extremely cumbersome. I have devised means whereby such floor members may be cast in a plurality of pieces each considerably smaller than the total area between supporting beams and these small primary members may be locked together by secondary keys cast in place after the primary members are erected. For the production of a strong floor at an economical cost it is highly desirable to use a flat arch and more particularly a groined arch.

A further object of my invention is to produce such a floor which when completed will have the arch form and which will therefore be very economical of material.

Further objects and advantages will be evident hereinafter.

Referring to the drawings which are for illustrative purposes only: Figure 1 is a

plan of a floor employing my invention in which various layers are shown broken away or shown in section to illustrate the construction used. Fig. 2 is a section on the line x^2-x^2 of Fig. 1. Fig. 3 is a plan of a portion of a concrete pier employing my invention, certain members being broken away or sectioned to better illustrate the construction. Fig. 4 is a section on the line x^4-x^4 of Fig. 3. Fig. 5 is a section through a subway showing the roof structure and a portion of the street thereover.

It is to be understood that this invention is applicable to any place where either a floor or roof is used in building construction whether such construction has for its object the production of a building, a pier, a subway, or any similar structure.

In the construction illustrated in Figs. 1 and 2 which is especially intended to apply to a building, columns 1 support concrete beams 2 and 3 which are suitably locked together. Reinforced concrete arch members 4, 5, 6, and 7 are cast at any convenient point about suitable reinforcement and after being allowed to properly set are placed on projections 8 on the beams 2 and 3. The primary member 4 is supported on the edges 9 and 10 and is curved upwardly to the center of the span, an opening being left on each side between the member 4 and the members 5 and 7. After the floor members 4, 5, 6, and 7 are placed, reinforcing rods 12 and 13 are set in the space between the members 9 and 10 and light forms are secured beneath this space and against the members 4, 5, 6, and 7. A concrete key 14 is then cast about the reinforcements 12 and 13 completely filling the space between the floor members 4, 5, 6, and 7. A body of filling material 15 is then tamped into place and any suitable floor 16 is placed thereover.

In the embodiment of my invention illustrated in Figs. 3 and 4 a concrete pier is illustrated having piles 20, upon which are supported a succession of beams 21. Floor members 22 which are exactly similar to the floor members 4, 5, 6, and 7 heretofore described are set in place on these beams and locked together by concrete keys 23, a floor 24 being cast over suitable filling material. The beams and floor may be extended to form cantalivered spaces 25 is desired.

In the form of my invention illustrated in Fig. 5, 30 and 31 are subway openings through which traffic may pass between

walls 32 and 33 which extend up and form a support for the roof structure coöperating with columns 34 for this purpose. Concrete beams 35 are placed on the members 32, 33, 5 and 34, and members 36, similar to the members 22, previously described, are set in place and locked by concrete keys 37, a roadway 38 being built thereon.

My invention should not be confused with 10 construction in which flat beams are used. The arch members 4 owing to their curved form are wholly in compression, exerting a side thrust against the beams 3 and against the key 14. The arch form, as is well understood, 15 is well adapted to concrete or masonry construction in which the materials used have little or no tensile strength. By its use in this connection floor members having large spans can be made very light and thin 20 and such members have great strength due to the material therein being wholly in compression. It should be further noted that by the use of a double arch resting at its two outer edges on beams at right angles 25 to each other a construction is produced which is entirely self-supporting without the keys so that any tying of reinforcement between the floor members or any false work is unnecessary.

30 I claim as my invention:

1. A floor construction comprising four beams forming a rectangular panel and four arch members resting thereon each arch member being supported on two adjacent edges of said panel, the other edges of the arch members being spaced from adjacent arch members to form a space for a concrete locking key.

2. A floor construction comprising a plurality of beams forming an open polygonal panel, and a plurality of floor members, each floor member resting on two adjacent beams of said panel each of said floor members being of substantially the same shape 45 and having a common meeting point at the center of the panel.

3. A floor construction comprising a plurality of beams forming an open polygonal panel each beam having a ledge formed thereon said ledges extending around the inner side of said panel, and a plurality of floor members, each floor member resting on the ledges of two adjacent beams of said panel each of said floor members being of 55 substantially the same shape and having a common meeting point at the center of the panel.

4. A floor construction comprising four beams forming a rectangular panel, four 60 floor members resting on said floor beams, each floor member being arched upward from two adjacent lower edges to two adja-

cent upper edges, the said adjacent lower edges resting on two adjacent edges of said panel and said two adjacent upper edges 65 being separated from similar edges on an adjacent floor member by a locking space, and a locking key cast in said locking space in such a manner as to lock said four floor members into a monolithic whole. 70

5. A floor construction comprising a plurality of beams forming an open polygonal panel, and a plurality of floor members, each floor member resting at its outer edge on two adjacent beams of said panel and being arched upwardly toward a common meeting point in the center of the panel. 75

6. A floor construction comprising a plurality of beams forming an open polygonal panel, a plurality of floor members, each 80 floor member resting at its outer edge on two adjacent beams of said panel and being arched upwardly toward a common meeting point in the center of the panel said floor members being mutually separated by a 85 locking space, and a locking key cast in said locking spaces in such a manner as to lock the floor members into a monolithic whole.

7. A floor construction comprising a plurality of beams forming an open polygonal panel, each beam having a ledge formed thereon said ledges extending around the inner side of said panel at a distance below the top thereof, and a plurality of floor 95 members each floor member resting on two of its adjacent outer edges on the ledge on two adjacent beams, each floor member being arched upwardly from said outer edges to a common central point inside said panel. 100

8. A floor construction comprising a plurality of beams forming an open polygonal panel, each beam having a ledge formed thereon said ledges extending around the inner side of said panel at a distance below 105 the top thereof, a plurality of floor members each floor member resting on two of its adjacent outer edges on the ledge on two adjacent beams, each floor member being arched upwardly from said outer edges to 110 a common central point inside said panel, said floor members being mutually separated by a locking space, and a locking key cast in said locking spaces in such a manner as to lock the floor members into a monolithic 115 whole.

In testimony whereof, I have hereunto set my hand at Los Angeles, California, this 24th day of July, 1914.

HENRY W. SCHLUETER.
